UNITED STATES PATENT OFFICE.

LOUIS C. SCHMIDT, OF SPRINGFIELD, ILLINOIS.

BANANA RACK AND COVER.

1,414,712.

Specification of Letters Patent. Patented May 2, 1922.

Application filed September 1, 1921. Serial No. 497,722.

To all whom it may concern:

Be it known that I, LOUIS C. SCHMIDT, a citizen of the United States, residing at Springfield, in the county of Sangamon and 5 State of Illinois, have invented a new and useful Banana Rack and Cover, of which the following is a specification.

The invention relates to racks for suspending and covers for surrounding and 10 protecting suspended bunches of bananas. The purposes of the invention are to provide simple and effective means for suspending a bunch of bananas and in conjunction therewith to provide a light, attractive and easily 15 cleaned cover to protect the enclosed bananas from flies; to provide a detachable cover of reticulate material to admit air and light and also to make visible the bunch of bananas enclosed by the cover; to provide a 20 cover having on its outside a representation of a bunch or bunches of bananas to attract customers; to provide simple and effective means for holding the cover around and away from the enclosed bunch of bananas; 25 to provide means for raising and lowering the fabric of the cover; to provide a bottom for closing the lower end of the cover and receiving detached or decayed bananas; and to provide other improved structural details.

30 The invention is illustrated in the accompanying drawing in which reference is hereby made, and will now be described in detail and the novel features thereof will be recited in the claim.

35 Figure 1 is a front elevation of a rack and cover embodying my invention;

Fig. 2 is a vertical longitudinal section through the same rack and cover, taken on the line 2—2 of Fig. 1, a suspended bunch of 40 bananas being shown in elevation; and

Fig. 3 is a horizontal transverse section through the same rack and cover on the line 3—3 of Fig. 1. The same reference numerals designate the same parts in all the views.

45 Bananas exposed for sale are usually supported on a hook 4 connected with a wire or rod 5 attached to the ceiling of a room, or other stationary structure. The banana bunch 6 is supported at a convenient height 50 above the floor.

The two longitudinal edges of meshed or netted fabric, preferably mosquito netting, are brought together and united by the stitching 8 to form a slip 7 open at both ends.

55 Adjacent to its upper end the fabric is gathered and a tape or tie 9 is wrapped

around the fabric on the wire 5 and detachably connects the fabric with the wire.

Metal arches 10 at right angles to each other have at their juncture a hole 12 60 through which the wire 5 extends. The terminal parts of the arches 10 are bent and shaped to form integral brackets 13 supporting sheaves 14 which rotate between the brackets.

65 Near the lower end of the slip 7 are loops 16 sewed on the fabric and containing a hoop 17.

A circular sheet-metal bottom-plate 18 enters the lower end of the slip and is approximately the same diameter as the 70 hoop 17.

75 Brackets 19 are riveted on the plate 18 and extend outwardly beyond the circumference of the plate.

There are four brackets 13 connected with the hoop 15 and supporting the sheaves 14; and four brackets 19 connected with plate 18 and supporting the sheaves 20, the respective sheaves 20 being vertically in line 80 with the respective sheaves 14.

There are four cords 21 co-acting with the sheaves 14 and 20. The upper end of each cord is attached to the hoop 15; the cord extends downwardly around the sheave 85 20, upwardly around the sheave 14 and downwardly to the hoop 17 and the lower end of the cord is attached to the hoop 17.

On the under side of the plate 18, at the 90 centre of the plate, is a fixed handle 22, used to raise and lower the plate.

The parts are so constructed and arranged that downward movement of the plate 18 will cause upward movement of the hoop 17 resulting in bunching the slip around 95 the hoop 15, so that the hook 4 will be accessible for putting on or taking off a bunch of bananas; and reversely, if the plate 18 will be pushed upwardly the hoop 17 will descend, carrying the lower part of the slip 100 with it and will stop on the plate 18 thereby completely closing the cover.

To use the cover, the parts being assembled as described; the upper part of the slip will be gathered around and tied on the wire 5. The plate 18 will be pulled downwardly to raise the hoop 17 to bunch the slip around the hoop 15. The bunch of bananas will be placed on the hook 4 and the plate 18 will then be pushed upwardly 110 to close the cover. To take bananas from the bunch the plate 18 will be pulled down-

wardly to cause the hoop 17 to raise the slip to give access to the bunch of bananas from which the desired bananas will be taken.

5 Having fully described my invention what I claim as new and desire to secure by Letters Patent is:

In a banana rack and cover, a supporting frame comprising crossed arches provided with sheaves and a hoop uniting said arches, in combination with a slip supported on said frame; a hoop attached inside said slip; a bottom plate inside the slip; sheaves on said bottom plate in vertical line with the 15 respective sheaves on said frame; and a

number of cords equal to the number of sheaves on said frame, each cord having one end attached to said frame, running downwardly around a sheave on the bottom plate, upwardly around the corresponding sheave 20 on the frame and having its other end attached to the hoop which is attached inside the slip.

Signed at Springfield, Sangamon County, Illinois, this 24th day of August, 1921. 25

LOUIS C. SCHMIDT.
